H. C. STOUFFER.

PUMP.

(Application filed Aug. 17, 1900.)

(No Model.)

UNITED STATES PATENT OFFICE.

HIRAM C. STOUFFER, OF MINERALRIDGE, OHIO, ASSIGNOR TO THE INDEPENDENT NOVELTY COMPANY, OF NILES, OHIO.

PUMP.

SPECIFICATION forming part of Letters Patent No. 673,789, dated May 7, 1901.

Application filed August 17, 1900. Serial No. 27,166. (No model.)

To all whom it may concern:

Be it known that I, HIRAM C. STOUFFER, a citizen of the United States, residing at Mineralridge, in the county of Trumbull and State 5 of Ohio, have invented certain new and useful Improvements in Pumps, of which the following is a specification.

The improvement which forms the subject-matter of this application is directed to a construction whereby in a lift-pump opposing pistons are actuated without separate pump-rod connections for the separate pistons. For this purpose I employ in combination the device known as the "lazy-tongs," a piston connected to each end thereof in alinement, a fixed connection of the lazy-tongs with the pump-cylinder meditately between the pistons, and a single pump-rod whereby the opposing pistons are caused to have equal stroke 15 to produce a continuous flow in the discharge of the water, and so far as I know and can find I am the first to employ the lazy-tongs as a connection for opposing pistons to obtain such continuous flow with a single pump-rod.

25 The accompanying drawings illustrate my improvement, in which—

Figure 1 is a vertical section of a pump-cylinder with opposing pistons, their lazy-tongs connection, and the single pump-rod, the pistons appearing as being controlled in the positions of moving away from a fixed mediate point of the lazy-tongs. Fig. 2 is a like view, the pistons being seen as in the limit of their movement toward each other. Fig. 3 shows 35 enlarged a vertical section taken at right angles to Fig. 1 to illustrate the construction by which the links of the lazy-tongs are braced against tendency to buckle at the fixed point of greatest strain and from which both pistons are actuated; and Fig. 4 is a transverse section of the pump, taken through the bracing means for the lazy-tongs.

It will be understood that the pump is submerged and has suitable pump-rod operative 45 connections. The opposing pistons 11 are each provided with a valve 2, arranged to open upward, and to each piston the lazy-tongs has a pivotal connection 3, while the lazy-tongs itself has a fixed pivotal connection 50 by a diameter-bolt 4, nutted at the walls of the cylinder. This fixed point has such

relation to the length of the lazy-tongs as to cause the lengthening and contracting movements thereof to give equal strokes to the pistons by one pump-rod 5, which is preferably rigidly connected to the upper piston by the yoke 6. The lazy-tongs is pivoted at its terminal links to the pistons, and in alinement with these pivots and meditately of its length the lazy-tongs is pivotally connected 55 to the pump-cylinder by the diameter-bolt 4, from which both pistons have their movements from the single pump-rod. It is by this mediate cylinder connection that I am enabled to employ the opposing pistons with 60 the lazy-tongs and with a single pump-rod to produce a continuous-flowing discharge and to give each piston a stroke governed by the length of the lazy-tongs. Obviously if the upper piston were dispensed with, the lazy- 65 tongs having the lower piston only and having a fixed connection at the top of the pump-cylinder, such construction would give only an intermittent lifting action upon the water. As the strain of both pistons is equally upon 70 the fixed pivot-bolt of the lazy-tongs, I provide a webbed brace 7, which stands inward from the cylinder-walls, as in Figs. 3 and 4, so as to abut against the links and support them against buckling. This webbed brace 75 I prefer to make by a screw-section, to which the pump-cylinder sections are screwed, so that the webs 7 stand inward against the fixed links 8 8, on which the lazy-tongs is extended and closed. For this purpose I pre- 80 fer to make the side links 8 bowed, so as to stand out on each side of the link. I also prefer to form the cylinder-web part with sleeve-bosses 14 14, Fig. 4, through which the pivot-pin of the lazy-tongs passes and gives the im- 85 portant advantage of a long bearing to the pin on each side of the lazy-tongs, which greatly increases the durability of the pin and also forms a better sealed joint for the pin in the cylinder-walls. 90

A foot-valve 9 is suitably secured at the lower end of the pump-cylinder to hold the water therein when the lower piston is on its descent; but inasmuch as the pump is preferably submerged it is obvious that the foot- 95 valve may be dispensed with.

The single pump-rod gives an easy and long

movement to the pistons, keeping the cylinder always full of water, while the single bolt 4 forms the fixed point from which the lower piston has its upward-and-downward movement 5 and the upper piston has its upward-and-downward movement, these movements of both pistons being produced by a single pump-rod.

In Fig. 1 the arrows 10 indicate the direction 10 of movement of the pistons in the ascent of the pump-rod and the arrows 11 indicate the upward flow of the water into the pump-cylinder between the pistons, while the arrows 12 show the flow of the water from the cylinder 15 above the upper pistons.

In Fig. 2 the arrows 13 show the directions in which the pistons will move on the ascent of the pump-rod.

While I prefer to connect the lazy-tongs 20 meditately of its length to the pump-cylinder to give equal strokes to the pistons, yet such connection may be made that will give unequal strokes to the pistons.

Obviously the pump-rod may be connected 25 directly to the lazy-tongs at a point between the pistons, by which construction a short stroke of the pump-rod would give a comparatively long stroke to the pistons.

I claim—

30 1. In a pump and in combination with a cylinder, a lazy-tongs pivoted meditately of its length to the walls of the cylinder, a

valved piston pivotally connected to each end of the lazy-tongs, a pump-rod rigidly connected to the upper piston, and means whereby 35 the lazy-tongs is braced and supported at their pivotal connection upon the cylinder-walls.

2. In a pump and in combination with a cylinder, a lazy-tongs pivotally connected meditately of its length to the pump-cylinder, a piston pivotally connected to each end of the lazy-tongs and having an upward-opening valve, and a pump-rod connected to the upper piston, and webbed braces on the inner 45 walls of the pump-cylinder for bracing the lazy-tongs at its cylinder connection.

3. In a pump and in combination with a cylinder, a lazy-tongs pivoted meditately of its length to the walls of the cylinder, a 50 valved piston pivotally connected to each end of the lazy-tongs, a pump-rod rigidly connected to the upper piston, and a webbed brace on the inner walls of the cylinder, each brace abutting the mediate links of the lazy-tongs 55 and formed with a sleeve-boss bearing for the pin.

In testimony whereof I affix my signature in presence of two witnesses.

HIRAM C. STOUFFER.
